UNITED STATES PATENT OFFICE.

GORDON B. JONES, OF WILSON, NORTH CAROLINA.

SUPPORT FOR OIL CANS.

1,417,327.

Specification of Letters Patent. Patented May 23, 1922.

Application filed June 13, 1921. Serial No. 477,187.

To all whom it may concern:

Be it known that I, GORDON B. JONES, a citizen of the United States, residing at Wilson, in the county of Wilson and State 5 of North Carolina, have invented new and useful Improvements in Supports for Oil Cans, of which the following is a specification.

This invention relates to attachments for 10 motor operated vehicles and aims to provide means for removably securing a container (such as an oil can or the like) beneath the hood of an automobile for the purpose of carrying a lubricant, in a convenient manner and at the same time provide for an economy of space.

Another object is the provision of means 20 for conveniently carrying a reserved quantity of lubricating oil, in an out-of-the-way place, so as to prevent injury to the contents of lockers or seat boxes, where reserved oil is usually carried.

With the above and other objects in view, the invention further includes the following 25 novel features and details of construction, to be hereinafter more fully described, illustrated in the accompanying drawings and pointed out in the appended claims.

In the drawings:—

30 Figure 1 is an elevation showing the invention secured to the radiator brace rod of an automobile.

Figure 2 is a sectional view on the line 2—2 of Figure 1.

35 Referring in detail to the drawings, wherein like characters of reference denote corresponding parts, the reference character 10 indicates a container, herein shown as of cylindrical formation and designed to receive a lubricating oil and for this purpose 40 is provided with a spout 11 having a mouth 12, which is normally closed by a screw cap 13. The container 10 may be of any other suitable size or shape that may be received 45 within the hood of an automobile so as to occupy the space between the top of the engine and the brace rod of the radiator, the latter being shown at 14.

The invention is designed to be supported 50 upon this brace rod 14 and for this purpose there is provided a sleeve 15 which is shown as rectangular in cross section and provided

along one side with a slot 16 which extends throughout its length. This sleeve is secured to the container 10 through the medium of straps 17, which provide hangers so that the container may be suspended from the rod 14 in the manner shown. 55

In order to removably hold the container in position there is provided a clamp which 60 includes a stationary jaw 18, secured within the sleeve 15 and a movable jaw 19. This last named jaw has secured along one side edge spaced bolts 20 which extend through the upper edge of the sleeve and are provided with winged nuts 21. 65

After the sleeve has been positioned over the rod 14 so that the latter will lie between the jaws 18 and 19, the winged nuts 20 may be adjusted so as to cause the jaws of the 70 clamp to tightly grip the rod.

By the use of the invention a reserved quantity of lubricating oil may be carried in a convenient place, so as to be at all times ready for use without danger of injury to 75 articles carried within the lockers or seat boxes of the automobile.

The invention is susceptible of various changes in its form, proportions and minor details of construction and the right is herein reserved to make such changes as properly fall within the scope of the appended 80 claims.

Having described the invention what is claimed is:—

1. The combination with the radiator brace rod of an automobile, of a container, a longitudinally slotted sleeve carried by the container for receiving the brace rod and means located within the sleeve for removably securing the container to the brace rod. 85 90

2. The combination with the radiator brace rod of an automobile, of a container, a longitudinally slotted sleeve carried by 95 the container for receiving the brace rod, a clamping bar located within the sleeve and means extending through the sleeve and connected to the clamping bar for adjusting the latter to removably secure the container 100 to the brace rod.

In testimony whereof I affix my signature.

GORDON B. JONES.
